Inventor:

*Joseph Siegel,
by Parker Cook
Atty.*

UNITED STATES PATENT OFFICE.

JOSEPH SIEGEL, OF DETROIT, MICHIGAN, ASSIGNOR TO AMERICAN LADY CORSET COMPANY, OF DETROIT, MICHIGAN, A CORPORATION OF MICHIGAN.

GIRDLE.

Application filed October 25, 1926. Serial No. 144,106.

My invention relates to new and useful improvements in girdles and has for an object to provide a garment which will snugly encircle the form of the wearer.

5 Still another object of the invention is to provide a girdle having hose supporters secured to certain portions thereof so that when the garment is in use and the hose supporters fastened to the stockings, the 10 girdle will be tightly anchored in place and cannot ride up or slip up on the wearer.

Still another object of the invention is to provide a girdle with front and back pieces; elastic inserts, shorter in length than the 15 front and back portions and a plurality of hose supporters crossing beneath the elastic inserts to thereby tightly anchor the garment to the figure.

With these and other objects in view, the 20 invention consists in certain new and novel arrangements and combination of parts as will be hereinafter more fully described and pointed out in the claims.

Referring now to the drawings showing a 25 preferred embodiment of the invention,

Fig. 1 is a view of the garment in its open or outstretched position.

Fig. 2 is a side view showing the garment as it will appear on a human form.

30 Fig. 3 is a similar front view, and

Fig. 4 is a rear or back view.

Referring now to the drawings, more in detail, there is shown in Fig. 1, a girdle comprising the back piece 1, which is preferably formed of an inelastic cloth material similar to that used in the manufacture of all corsets. The material, or girdle as a whole, is reinforced by the plurality of ribs or stays 2 which extend throughout the 40 width of the garment.

In the formation of this garment, there is secured to the opposite ends of the back piece 1, the two pieces of elastic material 3, which pieces are designed to stretch horizontally rather than vertically, and, as may be seen in Fig. 2, the length of the back piece and elastic material is such that these two pieces of elastic material are arranged to come directly over the hips of the wearer, 45 so that a certain freedom of movement is obtained which would not otherwise be the case.

As may be seen in the several figures, the front of the garment is formed preferably of

two pieces, that is, there is a piece 4 attached along the free edge of one of the elastic pieces of material 3. This front piece 4 is also reinforced by three stays 5 and is provided along its free edge with the usual row of hooks 6.

The other end of the garment comprises the piece 7, which, together with the piece 4, forms the whole front of the garment. Along the edge of this piece of material are the usual eyelets 8 to receive the afore- 65 mentioned hooks.

The girdle is relatively narrow in width, so that it will not encumber the wearer, and at the same time will support the stockings and hold the body in straight lines as is 70 the style at the present time.

It is to be noticed that the elastic pieces 3 are shorter in length than the width of the garment so that two notches or indentations 9 are present, which, of course, allow the 75 portions 1, 4 and 7 to adjust themselves to the shape of the wearer, especially at their lower edges.

Referring now to one of the principal parts of the invention, attention is called to the 80 plurality of hose supporters attached to the lower edge of the garment. It will be seen that a supporter 10 is fastened to a corner 11 of the piece 4 and right at the one edge of the indentation 9. A supporter 12 with two straps 13 and 14 at its upper edge is also sewed to the opposite side of the indentation 9, as may be seen at the point 15. The supporter 10 is now designed to extend between the straps 13 and 14, of the supporter 12, as 85 90 may be clearly seen in the several views.

In a like manner, the hose supporters for the other leg are positioned at the points 16 and 17, a supporter 18 passing between the straps 19 and 20 of the supporter 21.

Referring now to Figs. 2, 3 and 4, and first to Fig. 3, it will be noticed that the supporter 10 fastens to the stocking 22 in the rear, whereas the supporter 12 with a double strap will extend to the front of the stocking. In a like manner the hose supporter 18 comprising the single strap will be secured to the stocking in the rear, whereas the supporter with the double strap will be secured to the front of the stocking. The pull, therefore, on the supporters will tightly anchor the girdle to the wearer, the rear portion of the garment being pulled from the 95 100 105

front of the stocking and the front portion of the girdle being pulled from the rear of the stocking, thus snugly holding the girdle in its desired position.

- 5 From the foregoing it will be seen that I have provided what might be termed an athletic garment or girdle which is designed to be worn in the place of an ordinary corset, and will, in no way, hinder the movements of
10 the wearer.

By forming the girdle with the rear and front pieces, and the elastic inserts, designed to come over the hips, and by providing the indentations and hose supporters designed to
15 extend one through the others, the garment will tightly hug the wearer and hold the abdomen in place.

Furthermore, by placing the diagonal strain on the several parts of the garment,
20 even though the wearer be athletically inclined, the garment will be held tightly in position and will not ride up to the discomfort of the wearer.

I have spoken throughout the specification
25 as the garment being in the form of a girdle, but I do not wish to limit myself to an undergarment of such narrow width or height, as other garments of greater width or height might well be used. Also, although the
30 elastic is generally placed over the hips, elastic in other places might be used in the garment, or the elastic sections could be done away with.

I am aware that it is old to form a girdle
35 of front and rear pieces and to form girdles with indentations and notches, and to provide hose supporters with girdles, but I do not claim my invention broadly as such, but

what I do claim and desire to secure by Letters Patent is:—

1. A girdle comprising a front and rear portion, elastic inserts between said portions, hose supporters fastened to the front and rear portions and the hose supporters fastened to one portion extending through the
45 hose supporters fastened to the other portion, so that the pull from the front of the stockings will extend to the rear portion and the pull from the rear of the stockings will extend to the other portion of the girdle.

2. A girdle comprising front and rear portions of inelastic material, elastic material between the front and rear portions designed to come over the hips of the wearer, the elastic sections being of less height than the adjacent inelastic material, pairs of hose supporters respectively extending below the said elastic portions and each pair arranged to have one of their supporters pass through the other so that when the girdle is worn the strain will extend from the rear of the wearer to the front of the garment and vice versa, to thereby anchor the girdle in position.

3. A garment comprising a front portion and a rear portion and two sets of hose supporters, each of which has one supporter extending to the front portion of the garment and one to the rear portion of the garment, the supporters extending from the front portion in both instances respectively passing through the supporter fastened to the rear portion of the garment so that when the garment is worn it will be tightly held in position.

In testimony whereof I affix my signature.
JOSEPH SIEGEL.
